UNITED STATES PATENT OFFICE.

FORREST R. JONES, OF KNOXVILLE, TENNESSEE.

ROAD MACHINE.

Application filed October 1, 1924. Serial No. 741,052.

My invention comprises a roadway vehicle combined with a manually operable mechanism for completely and promptly controlling the gravitational discharge of a load of roadway material while the vehicle is either travelling along or standing still on a roadway. The roadway material may be either the screened or unscreened product of a rock crusher, and may contain pieces as large as four inches maximum dimension, or even larger, alone or mixed with smaller sizes including sand and dust, or the material may be either sand or dust alone.

The primary object is to provide, without using any mechanical drive, manually operable means to regulate the rate of discharge and to completely stop the discharge of the material at any instant while the machine is either travelling or at rest on the roadway.

A secondary object is to provide means to smooth the surface of the material dropped from the machine into holes of the roadway surface, the dropping and smoothing of the material both being accomplished while the machine, without stopping, is passing over the hole, thus preparing the newly deposited material for smooth riding traffic before any of the material is scattered or compressed by the traffic. Since the mechanism completely cuts off the discharge, there is no dribbling of the material over the good parts of the roadway. The machine can also be used to drop a load of roadway material smoothly and of uniform thickness on an extensive area of a roadway surface while the machine continues travelling at either a uniform or a variable speed.

I attain these objects by the mechanism illustrated in the accompanying drawings, in which—

Fig. 1 is a side view of the new device combined with an automobile chassis represented in outline; Fig. 2 is a top view partly broken away in order to show parts which would otherwise be hidden; Fig. 3 is an enlarged detail showing an additional member; Fig. 4 is a rear view of the upper part; Fig. 5 is a side view detail of a modification including an additional member; Fig. 6 is a rear-view detail, partly broken away, of the members shown in Fig. 5; Fig. 7 is a side view of a modified form of part of the mechanism, partly broken away; Fig. 8 is a rear view of the parts also shown in Fig. 7, partly in section; Fig. 9 is a sectional view of some of parts of Fig. 8 on the plane 9—9;

Fig. 10 is a modification of some of the parts shown in Figs. 7 and 8; Fig. 11 shows a generally modified form of the mechanism, with some of the parts partly broken away for clearness of representation; Fig. 12 is a diagrammatic representation of the relative positions of certain parts of Fig. 11.

In Figs. 1 and 2 the members of the automobile chassis to which the new parts of the mechanism are closely related are the sidebars A and B, the rear road-wheels C and D, and the crossbar E which connects the sidebars to the rear-axle housing. The upper part of each of the rear road-wheels is broken away.

Upon the rear ends of the sidebars A and B is rigidly fastened a bracket 1 also rigidly fastened to a hopper-type body 2. An angle-bar brace 3 is fastened in an upright position to the sidebar A and to the inclined front part of the body. A corresponding angle-bar brace (not visible in the drawing) is fastened to the sidebar B and to the body. These two braces and the bracket 1 together entirely support the body 2.

In the bottom of the body are four outlet openings, 4, 5, 6 and 7. The walls of the opening 4 are in the form of a chute 8 to which is hinged the ends of a trough-shaped cutoff 9 by means of two coaxial hinge-pins 10 and 10^a (Fig. 6). The cutoff 9 is for regulating the rate of discharge from the body, and for completely cutting off the discharge without dribbling.

Cutoff 9, shown by solid lines in its discharge position in Fig. 1, is joined by means of a connecting-rod 11 to a control handle 12 fulcrumed on a rod 13 supported by a bracket 14 rigidly mounted on the sidebar A. The connecting-rod 11 is hinge-connected to the lower end of the handle 12 by means of a hinge-pin 15 and to a lug 16 of the cutoff 9 by a hinge-pin 17. Moving the handle 12 from its solid-line position to its broken-line position (Fig. 1) swings the cutoff 9 from its solid-line position to its broken-line retaining position under the chute 8, in which latter position the cutoff prevents material from dropping through the outlet opening 4.

The outlet opening 5 has for its control mechanism a chute 18 (Fig. 6), a cutoff 19, a connecting-rod 20, a hinge-pin 21, a handle 22 and a hinge pin 22^a, all of which are respectively similar to the parts of the control mechanism for the outlet opening 4.

The handle 22 is fulcrumed on the rod 13 and 50 are duplicated respectively by the also used as a fulcrum for the handle 12.

In Fig. 2 the line V—V represents the median plane relative to which the entire 5 new mechanism is symmetrical. This plane V—V is perpendicular to the axis of the rear road-wheel axle at the middle of the axle. The mechanism for controlling the dropping of roadway material through the 10 outlet openings 6 and 7 is a symmetrical duplicate, relative to the medial plane V—V, of the mechanism described above herein for the control of the dropping of material through the outlet openings 4 and 5.

15 Of the mechanism for controlling the dropping of material through the outlet openings 6 and 7, the parts which are shown in Fig. 2 are:—The cutoffs 23 and 24; the connecting-rods 25 and 26; the hinge-pins 20 27 and 28; the handles 29 and 30; the hinge-pins 31 and 32; the rod 33; and the bracket 34.

The body 2 is divided into two compartments by the vertical partition plane 35, so 25 that different kinds of materials can be carried separately at the same time.

A seat 36 is of a dimension, in the direction of the sidebars A and B, sufficient to accommodate a truck driver and two operators, the latter swinging the cutoffs on 30 their hinges. A cross-bar 37 is bolted to the sidebars A and B so as to serve as a footrest for the two operators.

A drag-bar 38 is connected to the rear 35 part of the body 2 by means of four chains, 39, 40, 41 and 42, together with two eye-bolts 43 and 44 threaded into the drag-bar, one of the eye-bolts near each end of the drag-bar, and two eye-bars 45 and 46, one 40 on each side of the body 2. The two chains 39 and 40 alone serve to trail the drag-bar in its solid-line position behind the body when the roadway surface is level or not inclined sidewise, but when the roadway is 45 inclined sidewise one of the diagonal chains acts to prevent the drag-bar from creeping toward the lower side of the roadway. Thus if the roadway surface slopes downward in the direction from sidebar B to sidebar A, then the diagonal chain 41 prevents the 50 drag-bar from swinging toward sidebar A.

For transporting the drag-bar 38 during long hauls without depositing roadway material, the following members are provided 55 near the top of the body 2:—An upper angle-iron 47 and a lower angle-iron 48 (Figs. 1 and 4) are fastened together and to the rear wall of the body near the right-hand side by means of the rivets 49. An upright wedge 50 fits freely into suitable slots in the projecting arms of the angle-irons 47 and 48. The space between the upper and lower projecting arms is wedge-shaped and of the greatest height at the free ends of 60 the projecting arms. The parts 47, 48, 49 65

and 50 are duplicated respectively by the parts 51, 52, 53 and 54 at the same level and near the left-hand side of the body. The carrying position of the drag-bar 38 is shown by solid lines in Fig. 4, and by the 70 broken-line circle (Fig. 1) tangent to the upper and lower angle-irons 47 and 48 and also tangent to the upright wedge 50. Decrease of the drag-bar diameter due to wear 75 allows the upright wedges 50 and 54 to settle lower so as to hold the drag-bar tightly.

When a depression in a roadway is about to be filled, the machine is driven slowly, but not stopped, and an operator sitting on the seat 36 and facing toward the rear of 80

the machine, watches the roadway surface to determine which cutoff is to be used for dropping roadway material into the depression. Then, as soon as the machine reaches the proper position, he opens the selected 85 valve-gate by pushing the corresponding handle from its broken-line position in Fig. 1 toward its solid-line position in the same figure and to an extent which is determined by both the rate of travel of the machine 90 and the size of the depression to be filled.

As soon as sufficient material has dropped into the depression the operator then swings the cutoff to its retaining position. The 95 machine continues its travel throughout the operation just described. As the machine travels further forward, the drag-bar is trailed over the material just dropped and smooths the surface of the material into 100 conformation with the roadway surface around the edge of the filled depression. If a depression to be filled is of large area, then two or more adjacent cutoffs may be operated to fill it. If there are numerous 105 depressions to be filled in a comparatively small area of roadway surface, then two operators can work more efficiently than one.

The use of the drag-bar as part of the machine is desirable in that when the drag-bar is so used it is not necessary to close 110 the road against traffic and the roadway surface is put into condition for use before any of the uninterrupted traffic has an opportunity to compact or scatter part of the material over the adjacent good surface as is apt to occur if the dropped material is left unsmoothed and unprotected while awaiting 115 separate means for smoothing. This applies more especially to cases of intense traffic on crowded highways and city streets.

By locating the control handles forward of the seat 36 where they are within reach of the driver, then the latter can act as both driver and operator with the aid of mirrors placed so that he can see the reflection of the part of the roadway that is under the rear part of the machine, which is of advantage when there are only a few depressions to be filled in a very large area of 120 roadway surface. This use of mirrors is 125 130 135

analogous to that on automobiles and street cars.

For spreading roadway material smoothly over the surface of a roadway, the location of the control handles forward of the driver's seat is desirable, for then, while the machine is traveling at considerable speed, the driver can operate the cutoff thus allowing the material to drop and scatter evenly over the roadway surface, and he can promptly stop the dropping of material whenever desirable. The use of the drag-bar is not necessary in this spreading operation.

In order to lock the cutoff 9 in its closed position, a lock-hook 55 is provided (Fig. 3) fastened to the seat 36 by an eye-bolt 56, and hooked into the eye of a screw 57 in the control handle 12.

In Figs. 5 and 6 an apron 58 is rigidly fastened to the lower rear part of the body by capscrews 59. The apron extends downward behind the cutoffs 8 and 18 and serves doubly as a means to prevent scattering of the roadway material during rapid swinging of the cutoffs to the retaining position and as a stop to limit the backward swing of the cutoffs. The apron is thin enough to have considerable elastic yield, and therefore may be utilized as a spring to put stress in the lock-hook 55 in order to hold the lock-hook in its locking position and to prevent rattling of the cutoff mechanism.

The modifications shown in Figs. 7, 8 and 9 relate to the chutes and cutoffs beneath the bottom of the body 2. In these figures the rear wall-plate of the body 2 has a downward extension 60 with two flanges 61 and 62 projecting rearward. The inclined front plate of the body 2 has a downward extension 63 with two flanges 64 and 65 projecting forward. A side-plate 66 is fastened to the flanges 62 and 64 by countersunk screw-bolts 67 and 68, and a similar side-plate 69 is fastened to the flanges 61 and 65 by the screw-bolts 70 and 71. The four parts, 60, 63, 66 and 69, thus form a chute suitable for any of the outlet openings of the body 2, and this chute is attached to the body 2 by the upward extension of each of the parts 60 and 63.

The cutoff 72 comprises two flat end plates 72^a and 72^b at the ends of a cylindrically curved bottom-plate 72^c. For convenience of description the lines where these three plates, 72^a, 72^b, and 72^c, are joined together are shown as if the plates were fastened only by spot welding instead of having continuously welded seams. End-plate 72^a is hinged to the side-plate 66 by means of the hinge-pin 73 supported by the side-plate 66 at one end and at the opposite end by an ear-plate 74 held in place by a space-bar 75 and countersunk rivets 76. Between the ear-plate 74 and the end-plate 72^a is interposed a washer-shaped ring 77

spot-welded to the end-plate 72^a and rotatable on the hinge-pin 73; also a washer-shaped ring 78, interposed between the side-plate 66 and the end-plate 72^a, is spot-welded to the hinge-plate 72^a and rotatable on the hinge-pin. Each end of the hinge-pin 73 is of reduced diameter and fits tightly in the corresponding hole, thus preventing rotation of the hinge-pin 73 relative to the side-plate 66 and ear-plate 74. The end-plate 72^b is similarly hinged to the side-plate 69 by means of the ear-plate 79, space-bar 80, washer-shaped rings 81 and 82, and a (hidden) hinge-pin like and coaxial with the hinge-pin 73. One of the important features of this hinge is that it can be made very thin in the direction of the axis of the hinge-pin 73, thus permitting close grouping of two or more cutoffs end to end after the manner shown in Figs. 2 and 6. Other features are that the space bar 75 prevents grit from falling on the rubbing parts of the hinge; also the ear-plate 74, when set to press its lower end against the ring 77, prevents rattling of the cutoff. 90

The hinge-pin 83 (Figs. 7 and 8), for the cutoff connecting rod 11 (of Fig. 1), passes through an extension 84 of the end-plate 72^b and through a bracket 85 riveted on the convex surface of the bottom plate 72^c. The hinge-pin 83 is held in place by means of a lock-pin 86.

In Fig. 10 a modified hinge-pin 87 for the cut-off connecting rod 11 extends almost completely across the curved bottom-plate 72^c of the cutoff and has a modified means of support for its smaller end. The members of the cutoff shown in part in Fig. 10 are sectional on a plane through the axis of the hinge-pin 87 and radial to the coaxial hinge-pins on which the entire cutoff swings. An end plate 88 has an extension 89 bent in under the bottom plate 72^c so as to support the smaller end of the hinge-pin 87. A lock-wedge 90 fits into a transverse groove in the hinge-pin 87 and bears against both the bottom-plate 72^c and the side-plate 72^b, thus holding the hinge-pin 87 rigidly in place with the lock-wedge and a shoulder of the hinge-pin pressing against opposite sides of the end-plate 72^b. A radial hole 91 can be used for a cotter-pin as a second means for holding the hinge-pin 87 in place. 110

The curved bottom-plate 72^c (Figs. 8 and 9) is placed at a considerable distance from the lower end of the chute 60—63—66—69 in order to obviate pinching or biting of pieces of the road material between the edges of the curved plate and the lower end of the chute when the cutoff is operated. The cutoff can therefore be surely and quickly operated provided that the maximum diameter of the largest pieces of road material handled is less, by a small amount, than the 130

distance between the curved bottom-plate and the lower end of the chute.

In Fig. 11 an ordinary trailer chassis is represented by one of its sidebars F, the road-wheels G and H, and the cross-piece J between the sidebars and the axle of the road-wheels. Both of the road-wheels G and H are partly broken away. An ordinary tilting body K is hinged to the sidebars by means of the hinge-rod L, and the forward end of the body is lifted by an ordinary mechanism consisting of the column M, winding-drum N, hand-crank O, sheave P, cable Q and bracket R.

Beneath the rear end of the tilting body K is a cutoff 92 hinged to the body by means of a hinge-pin 93. A lug 94 on the bottom of the cutoff 92 is hinged to a connecting-rod 95 by means of a hinge-pin 96. The forward end of this connecting-rod has a hinge-pin 97 which connects the rod to a handle 98 fulcrumed on a rod 99 supported by a bracket 100 rigidly fastened to the sidebar F.

The bottom of the tilting body K has an opening above the cutoff 92, as shown diagrammatically in Fig. 12 in which a portion of the bottom 101 of the body K, and also of the tailboard 102, are in proper position relative to the cutoff 92 when the latter is in its retaining position. The valve-gate 92 is moved from its retaining position by swinging it clockwise about the hinge-pin 93.

Since the cutoff 92 is sufficiently held by roadway material above it to prevent its swinging from its retaining position during the tilting motion of the body, the use of locking means is not required when there is a substantial amount of roadway material above the cutoff, and when the hinge-pins L, 93 and 96 are located in relative positions substantially as shown in Fig. 11 the moving of the body throughout its range of tilting causes only a slight movement of the handle 98, therefore the handle 98 can be used for operating the cutoff 92 for all positions of the tilting body K while the body is being tilted; and if the handle 98 is locked in its shown position, then the tilting of the body will not cause the cutoff to swing enough on its hinge-pin 93 to permit dropping of roadway material from the bottom of the body. A cutoff extending across the entire width of the body can be used and may be operated by a handle or handles rigidly fastened to the cutoff and extended so as to be operated by an operator riding on the truck.

A hopper-type body can be mounted forward of the rear wheels of a four-wheel trailer, or forward of the wheels of a two-wheel trailer, and then all of the sides of the body may be inclined.

For such a use as distributing ballast be-

tween and outside of the rails of a railway track, a ballast car whose body comprises a hopper and three cutoffs is applicable, the middle cutoff for dropping ballast between the rails and the other two cutoffs for dropping ballast outside of the rails on both sides of the track, together with means for smoothing the surface of the dropped ballast. If the railway car has two four-wheel trucks, then its body may comprise more than one hopper, each hopper having its own cutoffs.

As shown in Fig. 7, the distance between the curved bottom-plate 72^e and the lower end of the outlet is sufficient to admit an ordinary hand-shovel to remove material from the trough. Part or all of a body full of material can be thus shoveled out. When a cutoff trough relatively larger than that of Fig. 7 is used, as for larger pieces of material, together with the other parts of Fig. 7 unchanged in size or position, then the material can be shoveled out more rapidly than from the smaller trough. Fig. 12 also shows that material can be similarly shoveled out across the edge of the cutoff trough.

Shoveling from the cutoff trough, as just described, is convenient when building up a roadway surface against the planks of a bridge or culvert, along the rough edges of gutter stones, and around manholes.

I claim:

1. In combination, a roadway vehicle comprising a body for carrying loose material, a discharge opening in the lower part of the body, a nonclosing cutoff for retaining material in the body, and means to move the cutoff from its retaining position to its discharge position and then to its retaining position.

2. In combination, a roadway vehicle comprising a body for carrying roadway material, an outlet opening in the lower part of the body, a trough beneath the outlet, means for tilting and uprighting the trough, and means to limit the uprighting motion of the trough.

3. In combination, a roadway vehicle comprising a body for carrying loose material, a discharge opening in the body, a trough beneath the opening, means for tilting and uprighting the trough, and means to prevent the material from being scattered by the uprighting effect of the trough.

4. In combination, a roadway vehicle comprising a body for carrying loose material, a discharge opening in the body, a trough beneath the opening, means for tilting the trough, and a baffle plate which limits the tilting of the trough to one direction.

5. In combination, a roadway vehicle comprising a body for carrying loose material, a discharge opening in the body, a

trough beneath the opening, means to tilt and upright the trough, and means for the double function of limiting the uprighting motion of the trough and of preventing scattering of the material during the uprighting motion of the trough.

6. In combination, a roadway vehicle comprising a body for carrying loose material, an outlet opening in the lower part 10 of the body, a nonclosing cutoff for retaining material in the body, means to move the cutoff from its retaining position to its discharge position and then to its retaining position, and means to lock the cutoff in its 15 retaining position.

7. A road machine comprising a roadway vehicle having a body for carrying loose material, an outlet opening in the body, a nonclosing cutoff for retaining material in 20 the body, means to move the cutoff from its retaining position to a discharge position and then to its retaining position, and a drag-bar connected from each end to both sides of the body by chains adapted to trail

the drag-bar always directly behind the 25 body so as to smooth ready for traffic the surface of material dropped from the body and at the same time to prevent unrestricted traffic from reaching and scattering or compacting any of the material before 30 its surface is smoothed by the drag-bar.

8. A roadway vehicle comprising a body for carrying loose material, an outlet opening in the body, a nonclosing cutoff for retaining material in the body and controlling 35 flow from the outlet, a drag-bar connected from each end to both sides of the body by chains adapted to trail the drag-bar always directly behind the body so as to smooth ready for traffic the surface of material 40 dropped from the body and at the same time to prevent unrestricted traffic from reaching and scattering or compacting any of the material before 45 its surface is smoothed by the drag-bar, and means to rigidly support the drag-bar free of the roadway surface.

FORREST R. JONES.
